WELT CUTTER

Jeremiah Lee Bausher and Frederick Daniel Rickert, Reading, Pa., assignors to Infants Socks, Inc., Reading, Pa., a corporation of Delaware

Application February 2, 1948, Serial No. 5,797

7 Claims. (Cl. 66—147)

1

This invention relates generally to the art of knitting and more particularly to the separation of individual selvage welt tops.

Normally individual selvage welt rib tops as knitted by the cylinder and dial needles of a rib knitting machine acting upon an appropriate yarn form a single continuous tube in which the tops are connected to each other by a removable separating course of knitting. Customarily the tops are separated by cutting the said separating course by hand at a certain point on the tube and by pulling the said course out of the tube, usually at a point opposite the cutting point. The cutting and the removing of the separating courses are hand operations which are expensive and time consuming.

Accordingly it is an object of the present invention to reduce the cost and the time of separating tops by providing means whereby one of these operations, namely the cutting of the separating course, is performed automatically on the knitting machine, so that subsequently it is only necessary to pull this course to separate the tops. It is a further object of the present invention to provide a device which may be readily attached to any rib knitting machine making selvage welt rib tops to cut the separating courses thereof, and which is under control of the selvage welt itself. With this type of device no machine setting or control is required as the operation thereof is controlled automatically by each selvage welt as it comes into contact with the device. Accordingly when the machine is changed to knit different length tops, there is no adjustment needed for the device since the latter is operated solely by the presence of a selvage welt and will be operated more often with shorter top and less often with longer tops.

Additional objects and advantages of the separating course cutting device will be apparent from the following description of the same taken in connection with the accompanying drawings illustrating the invention.

Figure 1 is a front view of a portion of a conventional circular rib knitting machine showing the fabric passing through the take up rolls and showing the invention in place.

Figure 2 is a sectional view taken on line 2—2 of Figure 1.

Figure 3 is a view in perspective showing the separating yarn cutting device in detail.

Figure 4 is an enlarged view showing the end of the cutter in contact with the moving fabric.

Figure 5 is an enlarged view similar to Figure 4 but showing the hook shaped member of the

5 cutter caught in the moving fabric, tilting the cutter and about to cut the separating course.

Figure 6 is a partial view of the fabric showing the cut portion thereof, and

Figure 7 is an enlarged detail view showing the ends of the cutting members.

The Figure 1 shows a portion only of a conventional circular rib knitting machine sufficient to illustrate the use of the separating course cutting device on the tube of selvage welt tops made by the machine. The side frames of the machine are shown at 10 and 11 extending between the top plate 12 and the bottom plate 13. Upon the plate 12 is the usual needle and dial cylinders and a cam ring 14, while supporting the machine are the usual legs 15 secured to the plate 13. Located between the side frames are the usual take up rollers 16, 16 which in turning in the usual manner exert tension upon the fabric tube 17 passing therethrough as the latter is knitted by the cylinder and dial needles. These parts have not been shown in complete detail as they are well known in the art and operate in the usual manner.

20 The fabric tube 17 is made up of individual selvage welt tops 18 with the special stitch formations 19 between the same. In each of the special stitch formations 19 there is a small roll of ravelled fabric 20 caused by the casting off of all the cylinder needle loops. There are the several courses of relatively enlarged dial knit stitches 21 which form openwork and cooperate with the cutting attachment as will be explained. Then there is the selvage welt 22 connected to the last course 23 of the enlarged stitches 21 and forming the beginning edge portion of a top. The said last course 23 is the separating course and when this is cut at a certain point and pulled out of the fabric, the two adjoining tops are separated with a selvage edge on one of them. It is the object of this invention to provide mechanical means for cutting the said separating courses automatically at the proper point under control of the selvage welt stitch structures.

45 A tube spreader 24 of any suitable material such as wood or the like is inserted in the fabric tube 17 and remains within the same just above the rotating take up rollers 16, 16 as the latter cause the fabric to be moved under tension through the same and past the fabric spreader. One face of the spreader is undercut as at 25 for a purpose to be described.

The cutting attachment is shown in Figure 3 having the base member 26 at one end of which are the holes 27, 27 through which suitable bolts

may be placed to hold the attachment in place on the side frame 10 as shown in Figures 1 and 2. Centrally located on the base 26 is the elongated opening 28 by means of which the stud 29, undercut at 30, may be adjustably positioned. A bolt (not shown) passing through the opening 28 from the opposite face of the base 26 is threaded into the stud 29 and holds the same in place. A cup like hollow member 31 is adjustably secured on the reduced member 30 by means of the set screw 32, the end of the cup forming a base upon which the arm 33 is pivoted about the screw 34. The forward end of the arm 33 is enlarged as at 35 and has a channel 36 cut therein, the channel being covered by a plate 37 suitably held in place. Within the channel 36 at the bottom thereof is the fixed cutting blade 38 having the notched cutting edges 39. Also within the channel 36 and upon the fixed blade 38 is the moving cutting blade 40 having the hook shaped outer end 41, the outer peripheral surface of which is rounded as at 42 while the inner peripheral surface is formed into the hooked shaped cutting edges 43. A suitable spring 44 is fastened to the plate 37 at the forward end thereof and to a stud 45 projecting outwardly from the opposite end of the movable blade 40 to keep the cutter in opened position.

Pivoted secured to the stud 45 at one end thereof is the connecting member 46, the other end of which is connected to the plunger 47 of the solenoid 48 mounted in the bracket 49 on the other offset end 50 of the arm 33. A suitable contact switch 51, operated by the bracket 49 when the latter is in the dotted line position of Figure 2, is positioned upon one of the adjustable L-shaped brackets 52 while the other L-shaped bracket is suitably adjustably mounted upon the other end of the base member 26 by means of the elongated opening 53 therein and the bolt 54 and nut (not shown) passing therethrough. A wire 55 from the switch 51 and a wire 56 from the solenoid 48 lead to any suitable source of electric power, the solenoid and switch being in series and connected with the wire 57. The weight of the component parts is such that the portion of the arm 33 to the right of the pivot point 34 viewing Figure 2 is heavier than the portion of the arm 33 and the parts thereon to the left of the pivot point. This would tend to rotate the arm 33 clockwise, Figure 3, and this is prevented by the stop stud 58 projecting outwardly from the member 31. The operation of the device will now be described.

The cutting attachment is set upon the machine so that the outer smooth surface 42 of the cutting member 41 is in contact with the moving fabric tube and presses against the same. It will be remembered that the spring 44 holds the cutting blade in opened position and the spring is strong enough to cause the member 41 to press against the tube 17, as appears in Figure 4, as the latter moves downwardly. The contact between the tube 17 and the member 41 is in the channel opening 25 of the spreader 24 which positions and holds the tube at this point. As the tube moves downwardly it slides past the smooth surface 42 of the cutting blade 40 without rotating the arm 33, which is so counterweighted as to remain in the full line position of Figure 2 and Figure 4. However when the openwork 21 comes opposite the hook shaped member 41, the latter is under sufficient pressure to pass through the same and be caught therein with the loops on the hook shape cut-

ting edges 43. Further movement of the tube 17 under control of the take up rollers causes the entire arm 33 to be moved counter clockwise, Figure 2, to the dotted line position against the counterweight where the bracket 49 closes the switch 51 to actuate the solenoid. This causes the rod 47 to actuate the cutters, as appears in Figure 5, to cut several of the openwork courses including the separating course 23. The resulting hole in the fabric is shown in Figure 6. It is immaterial that several courses are cut so long as the separating course is among them. The attachment is positioned so that the separating course is cut at the proper point to be pulled out from the opposite side of the tube. The hook member 41 will not enter the tube 17 except at the openwork areas 21 as at other points the fabric is too dense and compact.

As the cutter operates in the dotted line position, Figure 2, the hook 41 is withdrawn from within the tube and after the cutting is done, the counterweighted arm 33 moves back to the full line position of Figure 1 where it is ready to enter the fabric when the next openwork area passes the same. The cutting action above described will then be repeated. The length of the cutting blades are adjusted so that after the hook enters the openwork and the cutter is actuated, the selvage welt is not cut.

It will be obvious that the invention provides means for automatically cutting the separating yarn course of selvage welt tops connected together and that the operation of the device is controlled by the selvage welt stitch structure itself thereby making it independent of the length of the tops or of any control by the machine.

We claim:

1. In a circular rib knitting machine of the type producing a continuous knitted tube of selvage welt tops connected by separating yarn courses in which the tube moves under tension from the needles to the take up rolls, a cutting attachment in contact with said moving tube having electrically operated cutting members, one of said members being adapted to pass through and be caught by the openwork in the tube preceding the selvage welts, said attachment thereafter being operated under control of further movement of the tube to cut said separating threads.

2. In a circular rib knitting machine of the type producing a continuous knitted tube of selvage welt tops connected by separating yarn courses in which the tube moves under tension from the needles to the take up rolls, an attachment pivotally mounted upon the side frame of the machine having electrically operated cutters pressing against said moving tube, said cutters having one member thereof hook shaped with the outer peripheral surface rounded and the inner peripheral surface formed into a cutting edge, said hook shaped member being adapted to pass through and be caught by the openwork in the tube preceding the selvage welts, said attachment thereafter being turned by further movement of the tube to operate and cut said separating threads.

3. In a circular rib knitting machine having means to produce a continuous tube of individual selvage welt tops connected by separating yarn courses in which the tube moves under tension from the needles to the take-up, a cutting attachment adapted to be positioned on the machine adjacent the tensioned tube at a point below the needle cylinder, said attachment having a cut-

ting member pressing against the outer surface of the moving tube and adapted to pass inwardly through and engage the openwork stitches preceding each of the selvage welts preparatory to severing the separating courses between successive tops.

4. In a circular rib knitting machine having means to produce a continuous tube of individual selvage welt tops connected by separating yarn courses in which the tube moves under tension from the needles to the take-up, a cutting attachment adapted to be positioned on the machine adjacent the tensioned tube, said attachment having a member pressing against the outer surface of the moving tube and adapted to pass inwardly through and engage the openwork stitches preceding each of the selvage welts, and means to withdraw said member from the tube to cut stitches engaged thereby to sever the separating courses between successive tops.

5. A cutting attachment as set forth in claim 4 in which the means to withdraw said member from the tube is under control of the moving tube itself.

6. In a circular rib knitting machine having means to produce a continuous tube of individual selvage welt tops connected by separating yarn courses in which the tube moves under tension

from the needles to the take-up, a cutting attachment adapted to be positioned on the machine adjacent the tensioned tube, said attachment having a pair of cutters in normally opened position in which one of said cutters is pressed against the outer surface of the moving tube and is adapted to pass inwardly through and engage with the openwork stitches preceding each of the selvage welts, and means to withdraw said cutter from the tube to close said pair of cutters thereby cutting stitches engaged therebetween to sever the separating courses between successive tops.

7. A cutting attachment as set forth in claim 6 in which the means to withdraw said cutter is made operable by the moving tube itself.
